UNITED STATES PATENT OFFICE.

UEL S. McMILLAN, OF SAN FRANCISCO, CALIFORNIA.

DEFIBERIZING REDWOOD-BARK.

1,344,180.

Specification of Letters Patent. Patented June 22, 1920.

Application filed November 26, 1919. Serial No. 340,772.

To all whom it may concern:

Be it known that I, UEL S. McMILLAN, a citizen of the United States, residing at San Francisco, in the county of San Francisco and State of California, have invented new and useful Improvements in Defiberizing Redwood-Bark, of which the following is a specification.

This invention relates to the defiberizing 10 of the bark of California redwood. California redwood or *Sequoia sempervirens* is indigenous to the Pacific slope. This bark is *sui generis* and is characterized by the presence of long loose fibers in layers alternating with layers of bast-fiber. The long 15 loose fiber, if properly preserved in defiberization, is admirably suited for paper pulp making, as amply proven by many laboratory tests conducted by the forestry department 20 of the United States Government.

In the present invention, I provide a method and apparatus for defiberizing redwood bark in a manner to remove the fiber without at the same time crushing and 25 grinding it into small particles. In the present form of my invention, this is accomplished by the use of a movable combing element, preferably in the form of a wire brush which acts upon the bark longitudinally of the grain or fiber.

In the accompanying drawings:

Figure 1 shows a vertical elevation, partly in section, of a suitable form of apparatus for practising my method.

Fig. 2 shows an enlarged or exaggerated view in perspective of a piece of redwood bark, the edge or thickness of the bark appearing at the front of the view.

Fig. 3 shows a diagram of a modified 40 form of combing element.

Fig. 4 shows the application of my invention to the bark as contained on a log, the log being passed beneath the combing element, which element is suitably mounted to 45 act upon the bark longitudinally of the fiber.

Fig. 5 shows an end elevation of a log containing bark, with the rotary combing element in position to defiberize the bark.

Merely for the purpose of illustration, I 50 show in Fig. 1 a conventional apparatus for performing my method. In a general way this apparatus comprises a combing element 10, in the form of a rotary wire brush, power- 55 driven at the desired speed, a guide member 11 for feeding the bark to the brush in

a manner to present the bark so that the brush will act longitudinally of the fiber or grain of the bark. A receptacle or conveyer 12 is positioned beneath the brush to catch 60 the defiberized material.

In Fig. 2 I show an enlarged vertical cross section of a slab of redwood bark wherein A indicates in exaggerated form the layers of bast-fiber, and B the intermediate 65 layers of long loose fiber. The bast-fiber is hard and brittle. Therefore, I may feed the bark to the combing element in such a way that the wire brush will act on the longitudinal edge face of the bark rather than the 70 longitudinal side face, since in so doing the wires of the brush will get in between the bast-fiber layers and tear away the other fibers without breaking up and crushing the long fiber. I may also feed the bark so 75 that the brush will act on the side face longitudinally of the fibers, as when working on a log. The important requisite is that the brush acts longitudinally of the fibers at all times. The long fiber will not thereby 80 be ground up or broken into small particles and will thus be better suited for paper pulp uses.

In Fig. 3 I show a modified form of combing element comprising an endless belt 13, 85 on the outer surface of which are arranged wires or yielding teeth 14. The belt is arranged and driven to operate longitudinally of the fiber.

An important advantage and use of my 90 invention is the application of it to a log, the bark of which has not been removed, as shown in Figs. 4 and 5. The rotary brush 10 may be mounted on a frame 15, beneath which the log is conveyed by suitable means 95 16. Thereby the bark is removed from the log and at the same time defiberized. This method of employing my invention saves 100 the expense and labor of stripping the bark from the log.

Heretofore the bark of redwood has been peeled off in the woods or at the mills, inasmuch as the logs cannot be successfully sawed with the bark thereon. This is because the stringy fiber of the bark quickly dulls 105 the teeth of the saw and being drawn into the pathway of the saw often causes the saw to spring out of its course. The bark, therefore, is generally pulled from the log by hand means and thereafter burned as waste. 110 Therefore, by my invention I not only eliminate the expense and labor of peeling the

bark from the logs but convert this bark into a valuable by-product.

By the foregoing described invention, the defiberizing of redwood bark is made comparatively simple and easy and the long fiber is not crushed or broken up, and hence it will produce a better and stronger paper.

While I have shown a carrier 16 for bringing the log into position beneath the brush, it will be understood that the brush may be applied to the log as the latter passes through a flume on its way to the mill. The bark need not necessarily be dry, and, in fact, I find that dampened bark is more easily defiberized than dry bark.

Various changes in the construction and arrangement of the several parts may be employed without departing from the spirit of my invention as disclosed in the appended claims.

Having thus described my invention, what

I claim and desire to secure by Letters Patent is:

1. The process of defiberizing wood which consists in subjecting the solid wood to a yielding combing action in line with the length of the fibers of the same.

2. A wood defiberizing machine comprising a hopper having front and rear walls, the rear wall extending below the front wall and a rotary wire brush defiberizer, the periphery of which extends into said hopper below said upper wall and backwardly adjacent the rear wall above the bottom of said rear wall.

In testimony whereof I have hereunto set my hand in the presence of two subscribing witnesses.

UEL S. McMILLAN.
